Patented Feb. 13, 1917.

FIG. 1

UNITED STATES PATENT OFFICE.

CHARLES W. DUNHAM, OF SWISSVALE, PENNSYLVANIA, ASSIGNOR TO THE UNION
SWITCH & SIGNAL COMPANY, OF SWISSVALE, PENNSYLVANIA, A CORPORATION OF
PENNSYLVANIA.

ELECTROMAGNETIC DEVICE.

1,215,508.

Specification of Letters Patent. Patented Feb. 13, 1917,

Application filed September 12, 1914. Serial No. 861,379.

To all whom it may concern:

Be it known that I, CHARLES W. DUNHAM, a citizen of the United States, residing at Swissvale, in the county of Allegheny and State of Pennsylvania, have invented certain new and useful Improvements in Electromagnetic Devices, of which the following is a specification.

My invention relates to electromagnetic devices.

I will describe one form of device embodying my invention, and will then point out the novel features thereof in claims.

In the accompanying drawing, Figure 1 is a view showing in perspective, one form of electromagnetic device embodying my invention. Fig. 2 is a view showing in side elevation a portion of the device shown in Fig. 1.

Referring first to Fig. 1, the device in the form here shown comprises a field member A and a movable armature B of magnetizable material. The field A comprises two L-shaped members of magnetizable material each having a longer leg 1 or 1^a and a shorter leg 2 or 2^a. The longer legs 1, 1^a are parallel, and the shorter legs 2, 2^a are also parallel but point in opposite directions and are separated by a spacing member 3 of magnetizable material so that the legs 1 and 1^a are offset in the direction of the length of the spacing member and also in the direction in which legs 2 and 2^a point. Attached to the leg 1 at the end opposite to the spacing member 3 is a pole-piece 4 of magnetizable material having a concaved pole-face 6 facing in the same direction as the leg 2; and attached to the leg 1^a at the end opposite to the spacing member 3 is a similar pole-piece 4^a having a similar concaved pole-face 6^a facing in the direction opposite to pole-face 6. It will be seen therefore that by virtue of the construction of the core, the concaved faces 6 and 6^a are offset from each other instead of being oppositely disposed as is usual in devices of this character.

The legs 1, 1^a are provided with windings 11 which are connected with a battery 13 and a circuit controller 14, so that the field A is energized or not according as circuit controller 14 is closed or open. This circuit controller may be operated by any desired means, but such means forms no part of my invention, hence is not shown herein.

The armature B, as here shown, is of the

Z-type, but the two legs 9 and 9^a of the Z are separated and offset from each other so that they are in operative relation respectively to the concave pole-faces 6 and 6^a. As here shown, the two legs 9 and 9^a are attached by screws 15 to a shaft 10 of magnetizable material, which shaft is provided with knife-edge bearings 21 adapted to rock on suitable supports not shown in the drawing. The armature is provided with a counterweight 20 which tends to cause rotation in clockwise direction as the device is viewed in the drawing, and the movement of the armature in response to the action of this counterweight is limited by a fixed stop 5 located in the path of the counterweight. The legs 9 and 9^a are so arranged on the shaft 10 that when the counterweight 20 rests on the stop 5, the outer edge of leg 9 is adjacent the upper edge of pole-face 6 and the outer edge of leg 9^a is adjacent the lower edge of pole-face 6^a. This is shown more clearly in Fig. 2. Then when winding 11 is energized, leg 9 is drawn downwardly by pole-piece 4, and leg 9^a is drawn upwardly by pole-piece 4^a, so that the armature is swung in counter-clockwise direction against the action of counterweight 20. In accordance with usual practice, the center of shaft 10 is at the center of curvature of faces 6 and 6^a, but the center of curvature of leg 9 is preferably slightly to the right of the center of shaft 10 so that as the armature swings in counter-clockwise direction the air gap between leg 9 and pole-face 6 is gradually reduced, and for a similar reason the center of curvature of leg 9^a is preferably slightly to the left of the center of shaft 10. The angle through which the armature is thus swung is limited by the engagement of a shoulder 16 on leg 9 with a surface 7 on pole-piece 4, and by the engagement of a similar shoulder 16^a on leg 9^a with a similar surface 7^a on pole-piece 4^a. These shoulders 16 and 16^a serve also as auxiliary armatures to hold the armature B positively in the extreme position to which it is moved by the field A. In accordance with usual practice, the shoulders 16 and 16^a are prevented from actual contact with surfaces 7 and 7^a by core pins 8, 105 in order to prevent sticking of the armature due to residual magnetism; as here shown, these core pins are located in the surfaces 7 and 7^a.

It will now be seen that, contrary to the

condition existing in a Z-armature device of the usual construction, the leg 9 is not influenced by pole-piece 4^a, and the leg 9^a is not influenced by pole-piece 4; that is, when the armature occupies the extreme position to which it is moved by the counterweight (as shown in Fig. 2), there is no tendency, as in the ordinary construction, for pole-piece 4^a to exert a turning effort on arm 9 tending to rotate the armature in clockwise direction, and similarly there is no tendency for the pole-piece 4 to exert a turning effort in the same direction on arm 9^a. By virtue of this fact, the armature may be caused to oscillate through a considerably greater angle than is possible with the usual construction of devices of this character. That is, with the usual construction the greatest angle of oscillation which can be secured in practice is about 75°, because if the legs of the Z are made longer than this they extend into the field of the opposite pole-pieces when the armature occupies its extreme deenergized position, and the armature will therefore not be moved out of this position under the influence of magnetic action. In a device constructed in accordance with my invention, however, the armature legs 9 and 9^a may extend through arcs of 90° and the pole-faces 6 and 6^a may likewise extend through 90°, so that oscillation of the armature through an angle of 90° may readily be attained. Greater angles of oscillation can be secured if desired by making the pole-faces and the legs of the Z greater than 90° in length.

Devices embodying my invention may be employed for any purpose for which oscillation of the armature through a comparatively large angle is desirable. They are especially adapted for use as the actuating motors for indicators employed in railway signaling. An indicator of this class usually comprises a miniature semaphore which is moved from a horizontal position to another position, and to conform with modern railway signaling practice it is frequently desirable that the latter position be vertical; hence the semaphore must move through an angle of 90°. Heretofore, when electromagnetic devices of the Z-armature type have been employed in such indicators, it has been necessary to interpose a link between the armature and the semaphore, or to provide other equivalent means for securing a greater angle of oscillation of the semaphore than of the armature. When a device embodying my invention is employed for this purpose, however, it may be so constructed that the armature swings through an angle of 90° and the semaphore may then be attached directly to the armature, thus avoiding a multiplying mechanism of any kind. This is indicated in Fig. 1, wherein a semaphore 17 is attached directly to an end of the armature shaft 10.

It will be seen that when the armature B is in the extreme position shown, that is, when counterweight 20 rests against the stop 5, the semaphore 17 is horizontal, and that when the device is energized, the armature swings 90° in counter-clockwise direction so that the semaphore is then vertical. The desired operation of the semaphore is thus secured by a device of simple construction, requiring no links or other motion-multiplying means.

It is understood that in the practice of my invention the entire device will usually be inclosed in a suitable casing, and that the semaphore 17 will be located in front of a face or dial which obscures the remainder of the device. The casing and dial are omitted from the drawing to avoid complication.

Although I have herein shown and described only one form of electromagnetic device embodying my invention, it is understood that various changes and modifications may be made therein within the scope of the appended claims without departing from the spirit and scope of my invention.

Having thus described my invention, what I claim is:

1. An electromagnetic device comprising a field member having two poles, an armature mounted to oscillate and having two members, said poles being offset along the axis of oscillation of said armature and said armature members being offset to be in operative relation to said poles respectively.

2. An electromagnetic device comprising a field member having two concave pole-faces facing in opposite directions but offset from each other along the axis of curvature of said pole-faces, and a Z-armature having its two legs offset along the said axis so that they are in operative relation to said pole-faces respectively.

3. An electromagnetic device comprising a field member having two concave pole-faces facing in opposite directions but offset from each other along the axis of curvature of said pole-faces, the arc of each pole-face being substantially 90° in length, and a Z-armature having its two legs offset along the said axis so that they are in operative relation to said pole-faces respectively, the arc of each armature leg being substantially 90° in length, whereby the armature is capable of oscillation through an angle of substantially 90°.

4. An electromagnetic device comprising a field member having two concave pole-faces facing in opposite directions but offset from each other, along the axis of curvature of said pole-faces, and a Z-armature having its two legs offset along the said axis so that they are in operative relation

to said pole-faces respectively, said legs being so disposed that the outer edge of one leg is adjacent one edge of its pole-face when the outer edge of the other leg is adjacent the opposite edge of the other pole-face.

5. An electromagnetic device comprising a field member and an armature mounted to oscillate, said field member having two 10 pole-pieces offset from each other along the axis of oscillation of said armature, and said armature having two members off-set along the said axis so that they are in operative relation to said pole-pieces respectively, whereby each armature member is 15 influenced by the corresponding pole-piece but not by the other pole-piece.

6. An electromagnetic device comprising a field member having two concave pole-faces facing in opposite directions but offset from each other along the axis of curvature of said pole-faces, a Z armature mounted to oscillate and having its legs offset along the said axis so that they are in operative relation to said pole-faces respectively, and means for biasing said armature away from the position to which it is drawn by said field member. 20 25

In testimony whereof I affix my signature in presence of two witnesses.

CHARLES W. DUNHAM.
